VIBRATOR-EXCITING ACTION

Filed July 14, 1947

UNITED STATES PATENT OFFICE

2,533,830

VIBRATOR-EXCITING ACTION

Benjamin F. Miessner, Harding Township, Morris County, N. J., assignor to Miessner Inventions, Inc., Harding Township, N. J., a corporation of New Jersey

Application July 14, 1947, Serial No. 760,795

10 Claims. (Cl. 84—237)

1

This invention relates to actions for the excitation of vibrators, such as the vibrators employed in musical instruments. The invention contemplates especially, though not in all aspects limitatively, instruments of the piano type, wherein tuned strings or other vibrators are percussively excited by hammers under the control of a keyboard. The description will accordingly be presented largely with relation to a piano.

In United States Patent No. 2,271,460 issued January 27, 1942 on an application of mine, I pointed out the relatively great complexity of a modern action of conventional design—involving, as it does, an escapement mechanism, usually in the form of a pivoted and biased jack, to permit rebound of the hammer from the string to a greater separation from the latter than that to which the hammer had been propelled on its way to the string; a checking mechanism, usually in the form of a back-check, to provide some limitation of the rebound and to assist in the function of the next-mentioned apparatus; and a repetition-aiding mechanism, typically (in a grand piano action) in the form of a specially mounted and biased lever, for reducing the extent to which the key must be released in order to place the action in condition for effective repetition of key operation.

In that patent I disclosed and claimed an action from which all three of the mechanisms just mentioned were eliminated, in which the new arrangements introduced were of inherently great simplicity, and yet by which excellent and in some respects improved performance was achieved.

In United States patent applications since filed (Serial No. 556,166, filed September 28, 1944 now abandoned; Serial No. 566,979, filed December 7, 1944, on which Patent No. 2,469,568 has since been issued; and Serial No. 707,879, filed November 5, 1946) I have disclosed modifications of and improvements on the actions disclosed in that patent.

While in its broader aspects the present invention has certain features in common with the inventions mentioned above, its preferred embodiments are specifically different therefrom in that they retain the back-check mechanism of the conventional action—still eliminating, however, the escapement and repetition mechanisms.

A prime requirement of a satisfactory action—over and above its elementary one of exciting the vibrator in the first place—is that the hammer or other vibrator-exciting member shall be precluded, upon rebounding from the vibrator after its original excitation thereof, from re-

2
rebounding or “bouncing” back into a further contact (or series of further contacts) with the vibrator. In conventional actions this preclusion is accomplished by the escapement mechanism, at the expense of entailing the need for both checking and repetition mechanisms. In the inventions mentioned above this preclusion is in general accomplished by the use of true viscous energy absorption and/or of suitable opposing impacts on the hammer. According to the present invention this preclusion is accomplished by a braking effect exerted on the hammer. Thus it is an object of my invention to achieve, in a vibrator-exciting action, a braking of the rebound of the hammer or other vibrator-exciting member sufficient to preclude a further contact of it with the vibrator.

In conventional actions such braking effect as the back-check may exert on the hammer is a wholly subordinate one, supplementing (for purposes other than further-contact preclusion) the relied-on effect of the escapement mechanism in precluding further hammer-vibrator contact. It is an object of my invention to use the back-check, or means of generally similar nature, as the prime means of precluding such further contacts.

In conventional actions the more effectively the back-check, in its subordinate role, may have braked the hammer, the poorer tends to be the condition of the action for any intended repetition of the excitation of the vibrator by repeated key operation. It is an object of my invention to utilize the back-check, or means of generally similar nature, to preclude further contacts of the hammer or other exciting member with the vibrator, without harmful effect on the repetition. And it is an object to provide an action with repetition characteristics improved over those of conventional actions.

40 It is an object of my invention to achieve, in a vibrator-exciting action, a dynamic braking of the rebound of the hammer or other vibrator-exciting member from the vibrator—i. e., a braking effect proportional to the need therefor.

45 It is an object to provide a generally simplified and improved vibrator-exciting action.

Other and allied objects will more fully appear from the following description and the appended claims.

In the description reference is had to the accompanying drawing, in which:

Figure 1 is an elevational view of one embodiment of my invention, by way of example in an action for a piano of the grand type;

Figure 1a is a cross-sectional view taken along the line 1a—1a of Figure 1;

Figure 2 is an elevational view of a portion of the apparatus of Figure 1 but illustrating the same with the components in positions which they occupy at a certain stage during operation;

Figure 3 is a fractional elevational view illustrating a modification of my invention in respect of the hammer structure, it being understood that this is capable of optional substitution for a corresponding portion of the structure of Figure 1;

Fig. 3a is a cross-sectional view taken along the line 3a—3a of Figure 3; and

Figures 4, 5 and 6 are diagrammatic illustrations of the motions of certain parts of the apparatus in the illustrated embodiments of my invention.

In Figure 1 the numerals 1, 2 and 3 respectively designate the front, intermediate and rear rails of the key-assembly portion of the piano action. Extending upwardly from the rail 2 is shown a pin 4, encircled by a bushing or pad 5; and a key 6 is shown pivotally assembled on that pin and resting on that pad. The front end of the key extends over the rail 1, which is provided with the guide pin 7 extending upwardly and freely into the key, that pin being encircled by the bushing or pad 8 underneath the key. The rear end of the key is shown in its normal position of rest against the top surface of the strip or pad 9, which in turn is secured on the top surface of the rear rail 3. Between the pivot pin 4 and the rear extremity of the key, the key 6 is provided with the upwardly extending capstan screw 10. The key assembly as so described will be recognized as well known.

Driven by the capstan screw 10, upon operation of the key 6 (i. e., down-stroke of its forward extremity), is the hammer 11. This may be considered as comprising the hammer head 12; the hammer stem 13, at the rear end of which the hammer head 12 is attached (in manner herein-after more detailedly described); the hammer butt 14, in which the forward end of the hammer stem 13 is secured; and the pad 16 secured to the lower surface of the hammer butt 14. The butt 14, and thereby the entire hammer 11, is pivoted at 17 to a flange 18, which in turn is secured to a suitable rail 19 in the action.

The hammer 11 is coupled to the capstan screw 10, so as to be driven by the key 6, through a suitable coupling member such as 57. This may be in the form of a cylinder, for example of metal, with each of its end portions spun over into end-closing formation excepting for a relatively small central aperture—as shown in Figure 2 for the upper end of the member 57. In and extending downwardly from the hammer butt 14 through the pad 16, a short distance rearwardly from the pivot 17, there is secured a small pin 53; and in and extending upwardly from the capstan screw 10 there is secured a small pin 54. The parts are so positioned that the pin 53 is disposed approximately above the pin 54. The coupling member 57 may extend from the pad 16 to the capstan screw 10, excepting that a pad 58 of thin felt or the like may intervene between the bottom of 57 and the top of the capstan screw. The pins 53 and 54 respectively extend freely through the respective apertured ends of the coupling member.

The string which the hammer 11 is to strike is shown as 20, horizontally disposed above and in the path of movement of the hammer head 12

when the hammer pivots about 17. It will be understood that upon operation of the key 6 the attendant upward movement of the coupling member 57 will rock the butt 14 upwardly about the pivot 17, carrying the hammer head 12 toward the string 20.

The capstan screw 10 may be so adjusted that at the conclusion of an abnormally slow operation of the key—i. e., one so slow that the coupling member 57 remains in contact (through 58) with the capstan screw and the pad 16 remains in contact with the coupling member—the active (top) end of the hammer head 12 will have been brought to a small distance from the string 20—a distance comparable to that to which in a conventional action the hammer head has been brought at the time of “tripping,” for example.

The normal position of the hammer will be fixed by the resting of the butt 14, through pad 16 and coupling member 57, against the capstan screw 10, and the resting of the rear end of the key through pad 9 on the rear rail 3. The downward displacement of this normal hammer position from the keystroke-end position will of course be determined by the distance through which the capstan screw 10 moves during keystroke—and this distance of capstan-screw travel is in turn established, as conventionally, by adjustments of the effective thicknesses of pads 8 and 5 (as by choice of the thicknesses of stacks 8a and 5a of paper or cardboard washers with which fixed-thickness pads 8 and 5 may be supplemented), which adjustments of course fix the length of keystroke (as well as the normal key level).

As a stop against “overshooting” of the hammer downwardly upon key release (due to momentary yieldings of various parts such as pads 16, 9 etc.), with consequent strain on the hammer stem 12, there may be provided on top of the key 6—and in the path tending to be traversed by the hammer tail 15 hereinafter mentioned—a pad 23 of soft felt or the like, of such a thickness that on downward hammer motion to slightly beyond normal hammer position the lower end of the hammer tail 15 will impinge against the pad 23—from which it will, however, normally have a slight spacing.

Simply by way of simplification of illustration, there has been omitted from Figure 1 any showing of the usual damper for the string 20; this may, however, be provided in any conventional manner.

When the key 6 is operated the hammer will be propelled toward the string, until the forward end of the key bottoms on the pad 8. At this point the movement of the key and of the coupling member 57 will be essentially stopped; in the case of stronger blows administered to the key, the key and coupling member will continue their movements for a small further distance while the pad 8 is being compressed to a slight degree, and/or may execute a small further excursion while the upward inertia of the rear portion of the key momentarily causes a slight lifting of the key from its resting on pad 5—but any such continuance or further excursion is at sharply reduced velocity.

The hammer has been propelled by the coupling member up to the time of key impingement on pad 8, and has acquired an upward inertia of its own. At this time, being free to continue its movement, it ceases to be propelled by the now-stopped or much-slowed coupling member, and moves on without discontinuity of velocity to

strike the string. It produces an initial upward deflection of the string; it then moves downwardly with the string as the latter accelerates from its deflected position back toward its normal position, thus starting a rebound from the string.

As the string passes through its normal position and decelerates in its downward movement, the hammer under its own inertia (as well as gravity) leaves contact with the string and continues its rebound downwardly through the small distance required to bring it into impingement against the coupling member 57—assuming the key to have remained in operated position since the propulsion of the hammer by it. Of course if the key has not remained in operated position (i. e., if it has been released promptly after being struck) the downward passage of the hammer will continue through the very substantial distance required to restore it to its normal (Figure 1) position. While it will tend to overshoot that position, there have already been described means (i. e., pad 23) for relieving any resulting strains—and the hammer will be so far from the string that any re-rebounding toward the string is quite harmless.

If, however, the key has remained in operated position the hammer, upon passing through the small distance required to bring it into impingement against the coupling member 57, will come into such impingement and will then, by its inertia, cause a temporary compression of various compliant members in the system, including the hammer stem 13, the pad 16, the pad 5, and various other compliances (including the equivalent compliance of the pad 8 if that is then being compressed by key pressure, in that there will be occasioned a temporary de-compression of that pad), the hammer moving downwardly at decreasing velocity while yielding up its energy to those compliances. The hammer will then be moved upwardly, by the release of the energy acquired by those compliances, at a velocity which increases until the hammer has reached the point at which it began the compression of those compliances, by which time all the energy is delivered to the compliances (reduced only by dissipation therein) will have reappeared in the hammer in the form of upward inertia.

The foregoing outlines the action of the hammer in the absence of appropriate counteractive measures. And it will be understood that if such counteractive measures are not applied, the hammer will respond to its own momentum by continuing on toward the string, and will re-strike the string excepting in the special case of a relatively weak original striking. Upon rebounding from the string after the re-striking, or dropping down again without re-striking in the special case just mentioned, the hammer will enter the second cycle of an oscillation to and from the coupling member 57 which oscillation may be considered to have begun when the hammer first rebounded from the string after the original, intentional stroke. The only limitation of the number of cycles of this oscillation, in the absence of counteractive measures, is provided by the gradual dissipation of energy in the system—and the hammer may re-strike the string in as many as several of the early cycles of the oscillation. It was to prevent such tonally ruinous occurrences that the escapement mechanisms of conventional actions were resorted to and are still employed.

According to the present invention I apply a braking force to the hammer during its oscillation to and from the coupling member 57; by such

application I limit the oscillation, which the hammer of course still attempts or tends to engage in, to a harmlessly low magnitude and rapid attenuation. I apply this braking force in progressively greater degree the higher the velocity of key operation, with the results not only that the braking parts are saved from needless wear, but also that full reliability of operation is insured. And I limit the application of braking force to the period of attempted oscillation of the hammer, not only avoiding interference with the prior propulsion of hammer to string, but also leaving the hammer quite unbraked by the time it concludes its attempted oscillation—with the result that there is no interference whatsoever (such as occasioned in a conventional grand-piano action by a tight engagement of hammer-tail with back-check) with immediate repetition.

20 The braking means according to my invention may typically be formed by a portion of the hammer; an element with which a part of that portion may enter into impingement at proper times, to result in the frictional relative movement which is characteristic of a braking action; and means for causing impingement between the elements at the proper times. The last-mentioned means may be included in one of the first two elements; it may be responsive to key operation; and in the embodiments of the invention herein disclosed it has been shown incorporated in the hammer.

25 In describing the embodiment of Figures 1-2 it is convenient first to describe the non-hammer element of the braking means. For this I may conveniently utilize, and I have illustrated, a back-check 40 generally of the conventional grand-piano type. It will be seen to comprise a rod 41 extending upwardly and slightly rearwardly from the rear portion of the key 6, a little to the rear of the hammer; a block 42 of wood or other relatively hard material secured on the top extremity of and supported by the rod 41; a 30 pad 43 of relatively soft felt or similar material secured against the upper forward portion of the block 42; and a facing 44 of leather or the like secured to the rear-top and forward-bottom portions of the block 42 and encircling the pad 43.

35 The front surface of the back-check for use in these embodiments is preferably slightly concave, along an arc centered below the hammer pivot 17, and the top surface a convex one smoothly progressing, along an arc formed by 40 a much smaller radius, rearwardly from the front surface. The result of this preferred construction is to provide, near the top elevational level of the back-check, a horizontal line or narrow region 48 whose separation from the 45 hammer pivot 17 is less than that of any other portion of the back-check.

45 The part of the hammer against which the back-check 40 exerts its braking force may be a hammer tail 15, generally similar to that conventionally provided in grand-piano actions. Such a hammer tail has been illustrated as 15, formed for example in the usual manner by a downward extension of the wooden core of the hammer head 12. While it is not indispensable, 50 I prefer to incorporate in the hammer tail 15, to form its rear surface, a facing 15a of leather or similar material. The hammer tail 15 is desirably so shaped that the bottommost portion of the rear surface is rounded off downwardly 55 and forwardly from the immediately higher por-

tion, which latter may be approximately arcuately shaped about the hammer pivot 17, the two portions merging relatively smoothly at the horizontal line or narrow region 11'.

The relative elevations of the regions 40' on the back-check and 11' on the hammer are preferably so established, by appropriate design of those two elements, that these regions are approximately opposite each other when the key, having been depressed very slowly, is being pressed against the pad 8 with force equal to that with which it is so pressed at the conclusion of a relatively strong blow on the key. The relative fore-and-aft positions of the back-check and hammer are preferably so established (and, for example, finely adjusted by bending of the rod 41) that the path of the back-check region 40' (which pivots about the top of pad 5) approximately intersects the path of movement of the hammer region 11' (which pivots about 17) under the same conditions. These conditions are those under which the parts assume substantially the positions illustrated in Figure 2.

The regions 40' and 11' are those at which impingement occurs at appropriate times between the hammer and the back-check. In the illustrated embodiments the means which causes this impingement at those times is comprised in the hammer 11. It may comprise a flexible member interposed in the hammer (e. g., in the stem 13), together with the mass (e. g., that of the hammer head and tail 12 and 15) supported by the flexible member.

In Figures 1 and 2 the material of the hammer stem 13 is shown as broken just forward of the hammer head by the short gap 13a. Into the stem portions immediately in front of and behind this gap is inset the horizontal leaf spring 13b. The hammer head is assembled in the usual manner on the portion of the stem immediately behind the gap; and as a means of positively retaining the assembly of this stem portion, spring and head there may be passed through all these elements the pin 13c—as more fully shown in Figure 1a. Around the portion of the stem immediately in front of the gap there may be placed the collar 13d, reinforcing the assembly of the spring in this portion; and through the collar, stem and spring there may be passed the retaining pin 13e.

It will be understood that the spring 13b between the two portions of the stem material constitutes a resilient or flexible portion in the stem; further, that this together with the effective mass of the hammer head and tail forms a mechanical oscillatory or vibratory system in which, after any displacement of the hammer head-and-tail assembly out of its usual angular position relative to the stem, that assembly will tend to vibrate back and forth about that position while resuming it.

The mass of the hammer head-and-tail assembly, typically centered near the center of the head 12, is further removed rearwardly from the pivot 17 than is the spring 13b. Accordingly when the key is depressed at substantial velocity, the inertia of the head 12 will cause the head to rock rearwardly about the spring 13b, deflecting the latter, while the entire hammer is starting its upward movement toward the string. This rearward rocking of the head will continue for an interval determined by the natural period of the vibratory system abovementioned, whereupon the head will execute a forward excursion to and

past its normal disposition relative to the stem, thus assuming a forward displacement from which it will in turn swing rearwardly again—and so on in a series of excursions which, in the absence of any other forces on the hammer head tending to modify that series, would constitute a typical train of vibrations eventually decaying to zero. The tail 15, and thus the region 11', will execute an entirely similar series of excursions excepting that, since the region 11' is below instead of above the spring 13b, its excursions will at all instants be opposite in direction to those of the head 12.

Meanwhile the hammer is being propelled toward the string. With a typical adjustment of the parts, including the stiffness of spring 13b relative to the effective mass of the hammer head-and-tail assembly, and assuming a relatively strong blow on the key, the path of the region 11' will typically be such as is illustrated by the curve B in Figure 5. In this figure the line AA represents the wholly arcuate path which would be followed by the region 11' on an upward movement of the hammer unaccompanied by any deflection of the spring 13b; the level OO represents the level of the region 11' when the parts are in their normal (Figure 1) positions; the level KK represents the level at which the region 11' will be maintained by key pressure against the pad 8 with force equal to that with which the key is so pressed at the conclusion of a relatively strong blow; and the level SS represents the level of the region 11' at the time of original striking of the string by the hammer.

This Figure 5, as well as the corollary Figures 4 and 6, are several times enlarged relative to the structural views of Figures 1 and 2.

The typical path B in Figure 5 shows that, upon the relatively strong key blow which it represents, the region 11' will rise in a path which for a substantial distance digresses forwardly from the slow-motion path AA, and which then re-approaches the latter path but does not reach it until the region 11' is above the level KK. Then crossing the slow-motion path (and thus ending the first half-cycle of the swing) the path B reaches the level SS and perseveres above it (representing deflection of the string); it is then deflected downwardly (representing the beginning of hammer rebound) while still at approximately maximum displacement rearwardly from the slow-motion path AA. Now representing a somewhat slower hammer motion, the path B re-crosses the path AA (ending the second half-cycle of swing) to digress again forwardly therefrom, and to pass below the level KK (representing impingement of the hammer against the coupling member 57 and compression of the several compliances as mentioned above). As it re-approaches the path AA it starts an upward movement (representing the beginning of hammer rebound). Crossing the path AA (and ending the third and entering the fourth half-cycle of swing) it digresses again rearwardly while executing a passage again above the level KK, after which it is shown again approaching the path AA and reverting toward the level KK, and coming to an end at the intersection of that path and that level.

The terminal portion of the path B reflects the effect of the back-check 40 on the motion of the region 11' (i. e., on the motion of the hammer head-and-tail assembly). It is therefore helpful to refer at this point to Figure 4, wherein the

path C is that of the region 40' on the back-check during the key-blow.

The path C begins at the point Q, representing the normal (Figure 1) position of the back-check region 40'. From Q it extends in a long-radius arc to intersect the path AA at approximately the level KK—which intersection at that level is the result of the preferred relative positionings of the regions 40' and 11' set forth above, and corresponds to the illustration of Figure 2. The line JJ indicates the approximate level at which the region 40' will have arrived when the key first touches the pad 8; it is thus at substantially this level JJ that there begins a deceleration of the motion of the back-check and its region 40', which deceleration continues until the region 40' comes to rest at the level KK.

The illustrations in Figures 4 and 5 of course do not in themselves express time. It will be understood, however, that at the time the region 40' has reached the level JJ, the region 11' will have approached the level KK; that at the time the region 11' has reached the level KK the region 40' will have progressed only part-way from level JJ toward level KK; and that by the time the region 40' has reached the level KK the region 11' will have progressed a considerable distance above that level.

Subject to slight modifications which will be understood to be established in any individual case by the particular configurations of the surfaces of back-check and hammer tail adjacent the regions 40' and 11' respectively, the criterion for non-impingement between those regions is that the hammer-tail region 11' (whose path is B, Figure 5) shall not at any instant lie, in the space system illustrated in each of Figures 4 and 5, in a position which is both (1) at any level from slightly above to substantially below the level at which the back-check region 40' then is, and (2) further separated leftwardly from the path AA than the back-check region 40' then is. Reference to Figures 4 and 5 in themselves shows that prior to the fourth half-cycle of vibration there is no possibility of impingement between the two regions, and that therefore the original trip of hammer to string is unimpeded—and the considerations set forth in the preceding paragraph provide an additional, though unnecessary, margin of safety against such impingement.

But in the terminal portion of the path B of the hammer region 11' in Figure 5—not traversed, of course, until after the back-check region 40' has reached the intersection KK-AA—the criterion for non-impingement is obviously violated. This violation begins at the beginning (designated as X) of the fourth half-cycle of swing. When the hammer region 11' reaches this point the rear surface of the hammer tail 15 a little above the region 11' will impinge on the back-check region 40'. As the upward hammer movement shown from point X continues, the rear surface of the hammer tail will be dragged along the back-check region 40'—the leather surfaces of the two, and to a greater degree the underlying felt 43 of the back-check, yielding slightly under the pressure of the two elements against each other. This provides a high degree of damping of the rebound of the hammer from the coupling member 57 and, by the time the hammer region 11' reaches the level KK, will have largely used up the energy of the hammer. At that time the hammer will typically have left a slight amount of energy, and so will pass upwardly slightly beyond coincidence of region 40' with level KK

(and may even momentarily break the engagement of hammer tail with back-check); the hammer will have by no means enough energy, however, to progress far toward the string, and so will drop back to a position of rest, or substantial rest, of the region 40' at the intersection KK-AA.

It is to be noted that at this time the criterion for non-impingement is again met and the elements, though typically just touching, will not be exerting any restraint on each other—a feature important for perfection of repetition.

A typical operation of the action has been illustrated in Figure 5 and described above for the case of a relatively strong blow on the key. With weaker key blows the nature of the path of hammer region 11' will shift somewhat—in general, so that the first half-cycle of vibration will end at a lower level than in Figure 5, and ensuing half-cycles will be altered attendantly (and their number in cases increased). But I have found uniformly that an action according to my invention which functions effectively with relatively strong key blows and resulting high velocities, functions effectively throughout the range of lower ones. Several factors contribute to this result, among them the sharply reducing amplitudes of vibration with reducing velocities; the substantial safety margin (unused at strong key blows in the case of the Figure 5 path, as above noted) as to unwanted interference with original hammer movement to the string; the sufficiency of lighter impingements, in whatever cycle occurring, to damp the hammer oscillation, the lower the hammer velocity; and, importantly, the reducing need (which reaches zero with still-finite key velocities) for hammer-oscillation-counteracting measures, the lower the hammer velocity—resulting from the relative harmlessness of a hammer oscillation to and from the coupling member so long as it is of a low enough magnitude to insure positively the absence of any re-striking of the string.

It is to be understood that even for strong key-blows the shape of the path of the hammer region 11' may vary very considerably from that shown in Figure 4, without harmful effect or departure from the principles of my invention. Thus in Figure 6 I have illustrated the path of the hammer region 11' in an action differently adjusted—for example, with a stiffer spring 13b in the hammer stem 13, resulting in a shorter natural period of vibration of the hammer head-and-tail assembly (the stiffness of this spring, or the equivalent member, being understood to be a characteristic which should be related to the particular hammer with which it is to be used to produce the desired natural period).

In Figure 6 the path of the hammer region 11' is designated as D. It shows the path reaching a maximum forward displacement from the slow-motion path AA slightly less than that of path B of Figure 5, but crossing the path AA (and ending the first half-cycle) at a level somewhat below KK. The curve D reaches the level SS at approximately its maximum displacement rearwardly from the path AA, and goes beyond SS during string deflection. By the time the string has returned to its normal position the curve D has passed into the third half-cycle; this it completes while the hammer is engaged in compressing the several compliances after impinging on the coupling member 57. That compression continues somewhat after the curve D has passed into the fourth half-cycle, in the remainder of which the curve D comes to its conclusion at the

intersection KK-AA, representing the coming to rest (or substantial rest) of the hammer.

It will be recognized that with the path D the criterion for non-impingement is still not violated during the original trip of the hammer to the string—though the safety margin is only a fraction of that which existed in the case of the curve B of Figure 5. The braking action is still performed, however, with full effectiveness—in this instance throughout the entire fourth half-cycle, during all of which the criterion for non-impingement of the regions 40' and 11' is violated very effectively.

There are intended no unnecessary limitations as to various features of my invention, or to the characteristics of the particular element paths which I have illustrated by way of example in Figures 5 and 6. Thus for example while I find it thoroughly satisfactory to make the fourth half-cycle of vibration the one in which the impingement and the braking action occur, another half-cycle or a group of half-cycles may alternatively be selected for use. Again, for example, I may otherwise provide the flexible or resilient member in the means which brings the brake into play. Such a variation I have illustrated in Figures 3 and 3a wherein, instead of forming a stem 13 in two spring-joined sections, I employ the integral stem 13' very substantially thinned (by removing top and bottom material from an originally circular stem) at the region 13'' closely adjacent the hammer head; if desired, this thin region 13'' may be joined to the hammer butt 14 by a stem section 13''' along which the original stem diameter is only progressively restored.

These and other modifications which will suggest themselves to those skilled in the art will not necessarily involve departure from the spirit of my invention, the proper scope of which I undertake to define in the appended claims.

I claim:

1. In a key-operated action for exciting the vibrator of a musical instrument, a hammer movable to strike the vibrator; means, moved by the key in a hammer-propelling path and retained in a limiting position in that path while the key remains operated, for propelling the hammer toward the vibrator, to and from which means while in that position the hammer attempts to oscillate after striking the vibrator; normally inoperative means for braking the hammer; a flexible member included in said braking means to permit its establishment in operative condition; and inertia means included in said braking means and cooperating with said flexible member to maintain the braking means in inoperative condition during hammer propulsion but to place the braking means in operative condition during such attempted hammer oscillation.

2. In a key-operated action for exciting the vibrator of a musical instrument, a hammer element movable to strike the vibrator; means, moved by the key in a hammer-propelling path and retained in a limiting position in that path while the key remains operated, for propelling the hammer element toward the vibrator, to and from which means while in that position the hammer element attempts to oscillate after striking the vibrator; a back-check element moved, normally free of interference with the hammer element, by the key; a flexible member included in one of said elements to permit impingement between said elements; and inertia means included in said one element and cooperating with

said flexible member to maintain said elements free of each other during hammer-element propulsion but to cause impingement between said elements during such attempted hammer-element oscillation.

3. In a key-operated action for exciting the vibrator of a musical instrument, a hammer element moved by the key, upon operation of the key, to strike the vibrator; a back-check element moved by the key in proximity to the hammer element; and a resilient member included in one of said elements and supporting a portion thereof and forming with said portion a vibratory system placed in vibration by the key upon operation thereof, said elements and their paths of movement being disposed relatively to each other to cause impingement between said elements during an excursion of said system opposite to the excursion initially occasioned by key operation.
4. In a key-operated action for exciting the vibrator of a musical instrument, a hammer element moved by the key, upon operation of the key, to strike the vibrator; a back-check element moved by the key in proximity to the hammer element; and a resilient member included in one of said elements and supporting a portion thereof and forming with said portion a vibratory system placed in vibration by the key upon operation thereof, said elements and their paths of movement being disposed relatively to each other to cause impingement between said elements to occur for the first time following key operation in the fourth half-cycle of vibration of said system occasioned by that operation.
5. In a key-operated action for exciting the vibrator of a musical instrument, a hammer moved by the key, upon operation of the key, to strike the vibrator; a resilient member included in said hammer and supporting a portion thereof and forming with said portion a vibratory system placed in vibration by the key upon operation of the key; and an element positioned to be impinged on by a part of the hammer during an excursion of said system opposite to the excursion initially occasioned by key operation.
6. In a key-operated action for exciting the vibrator of a musical instrument, a hammer moved by the key, upon operation of the key, to strike the vibrator; a resilient member included in the hammer and supporting a portion thereof and forming with said portion a vibratory system placed in vibration by the key upon operation of the key; and an element positioned to be impinged on by a part of the hammer for the first time following key operation in the fourth half-cycle of vibration of said system occasioned by that operation.
7. In a key-operated action for exciting the vibrator of a musical instrument, a hammer movable to strike the vibrator; means, retained in a hammer-propelling path and limitedly moved therein by the key, for propelling the hammer toward the vibrator, to and from which means while in the position to which it has been moved by key operation the hammer attempts to oscillate after striking the vibrator; an element past which a part of the hammer moves; and means, included in said hammer and comprising a flexible member and mass supported by said member, for causing said hammer part to impinge on said element during such attempted hammer oscillation only.
8. In a key-operated action for exciting the vibrator of a musical instrument, a hammer movable to strike the vibrator; means, moved by the

key in a hammer-propelling path and retained in a limiting position in that path while the key remains operated, for propelling the hammer toward the vibrator, to and from which means while in that position the hammer attempts to oscillate after striking the vibrator; an element past which a part of the hammer moves at least substantially freely when the key is operated at low velocity; and means, included in the hammer and rendered effective by the key upon operation of the key at higher velocities, for causing said hammer part to impinge on said element during such attempted hammer oscillation.

9. In a key-operated action for exciting the vibrator of a musical instrument, a hammer movable to strike the vibrator; means, moved by the key in a hammer-propelling path and retained in a limiting position in that path while the key remains operated, for propelling the hammer toward the vibrator, to and from which means while in that position the hammer attempts to oscillate after striking the vibrator; an element past which a part of the hammer normally moves with at least substantial freedom; a flexible member included in the hammer to permit displacement of a portion thereof laterally from its normal path of movement; and inertia means in-

cluded in the hammer and cooperating with said flexible member to maintain said hammer part free of said element during hammer propulsion but to displace said hammer part into impingement against said element during such attempted hammer oscillation.

10. In an action for exciting the vibrator of a musical instrument, a hammer comprising a hammer head adapted to strike the vibrator, a stem pivotally supported at one of its ends and carrying said hammer at its other end, and flexible means interposed in said stem adjacent to said hammer head.

BENJAMIN F. MIESSNER.
